UNITED STATES PATENT OFFICE.

ARTHUR L. OTTO, OF PHILADELPHIA, PENNSYLVANIA, AND WILLIAM W. WATSON, CHARLES ANDERSON, AND ELLIOT M. UNDERWOOD, OF JAMESTOWN, NEW YORK; SAID WATSON, ANDERSON, AND UNDERWOOD ASSIGNEES TO SAID OTTO.

POR-T-LIGHT SCREEN.

1,272,990.

Specification of Letters Patent. Patented July 16, 1918.

Application filed May 10, 1918. Serial No. 233,660.

To all whom it may concern:

Be it known that we, ARTHUR L. OTTO, a citizen of the United States, residing in the city and county of Philadelphia, State of Pennsylvania, and WILLIAM W. WATSON, CHARLES ANDERSON, and ELLIOT M. UNDERWOOD, citizens of the United States, residing at Jamestown, in the county of Chautauqua, State of New York, have invented a new and 10 useful Port-Light Screen, of which the following is a specification.

Our invention consists of a portlight screen in which provision is made for connecting the gauze or screen-like member 15 with the collar or frame of the device in a convenient and firm manner, and admitting of the ready disconnection of the same.

It consists also of a ring-like reinforcement for the peripheral portion of the gauze or screen-like member, and the adaptability 20 of the same as a fixture on the latter, and permitting the removal as one of both said member and its reinforcement from the collar or frame of the device.

25 It consists further in providing the gauze or screen-like member with a bail for conveniently handling said member in its application to and removal from position, the same being mounted on ears which are connectible with the proper portions of the device by screws which are employed as means to prevent rotation of said member when occupying its operative position.

The invention is satisfactorily illustrated 35 in the accompanying drawing, but the important instrumentalities thereof may be varied, and so it is to be understood that the invention is not limited to the specific details shown and described, as long as they 40 are within the spirit or scope of the claims.

Figure 1 represents a side elevation of a port light screen embodying our invention.

Fig. 2 represents an elevation taken from the interior thereof.

45 Fig. 3 represents a diametrical section thereof on line 3—3 Fig. 2.

Fig. 4 represents a transverse section of a portion on line 4—4 Fig. 2 on an enlarged scale.

50 Fig. 5 represents a section of the peripheral portions of the gauze and the reinforcement and connecting member of the latter.

Fig. 6 represents a section of portions of the device shown at the right hand of Fig.

3 on an enlarged scale, the sections being 55 separated one from the other.

Fig. 7 represents a transverse section of a portion of a modification.

Similar numerals of reference indicate 60 corresponding parts in the figures.

Referring to the drawings.

1 designates a circular collar forming a frame composed of the side rim 2 and the flange 3 inturned from one side of the periphery thereof. On the back or inner face 65 of said flange is seated freely the sheet 4 of gauze or screen-like material of metal, on the inner side of the peripheral portion of which is the annulus or ring 5 of metal which is rigidly secured to said portion by solder as 70 at 6, thus reinforcing said portion and rigidly connecting the latter with said ring whereby they may be located and removed as one.

In the outer peripheral edges of said ring and sheet are the spaced apart slots or recesses 7 and 8 respectively, said slots being left uncovered by the solder employed, see Fig. 5, and in the side rim 2 of the collar are the spaced apart lugs 9 which are struck up or punched in from the material of said rim so as to be projected inwardly into the collar, they being adapted to be passed through registering pairs of said slots 7 and 8, and then by rotating said ring and sheet the rear 75 faces of the ring ride under said lugs, and the latter overhang said ring whereby the sheet is held tightly on its seat on the flange 3, and so firmly connected with the collar, this being accomplished in a simple and 80 practical manner.

In order to retain the ring and sheet in adjusted position on the collar, openings 10 are made through the ring, openings 11 are made through the sheet, and openings 12 95 are made through the flange 3, see Fig. 6, said openings being adapted to register, and through the same are passed the screws 13 whose threaded ends appear on the exterior of said flange where they have fitted on them the nuts 14 which are adapted to be tightened against the outer face of the flange 3, the effect of which is evident.

In order to provide convenient handles for applying and removing the ring and sheet to and from position on the flange 3, we employ the bails 15 which are mounted 105 in ears 16, the latter being secured to the

band 5, and consequently to the sheet and collar by the screws 13 which also pass through openings in said ears and provide common connections for the band, sheet, and 5 bails with the collar.

It is evident that by removing the nuts and screws the ring and sheet may be rotated, and when the slots in the same are in register with the lugs 9, the sheet and ring 10 may be withdrawn from the flange and consequently disconnected and displaced from the collar, it being seen that as the ring and 15 peripheral portion of the sheet are connected as one, the sheet may be readily removed and reapplied as one to and from the collar without liability to bend, especially on its periphery owing to the fact that said periphery is vastly reinforced by the ring and 20 solder, the latter remaining on the ring, an improvement in the art where sheets of the kind are soldered to the flange 3, as heretofore practised.

In lieu of the lugs 9 on the side rim of the collar we may employ pins, studs or screws 25 17, as shown in Fig. 7, they being passed through said rim and adapted to engage the inner side of the ring 5, the same as the lugs in the other figures.

Having thus described our invention what 30 we claim as new and desire to secure by Letters Patent, is:—

1. In a port light screen, a collar, a gauze-like sheet, and a ring, the latter being rigidly connected with the peripheral portion 35 of said sheet as one, and both freely seated on said collar.

2. In a port light screen, a collar, a gauze-like sheet, a ring on the peripheral portion of said sheet, and means on the side rim of 40 said collar adapted to project into the collar

and overhang said ring, said ring and sheet having in the peripheral portions slots through which said means may pass in the application of the same to said collar.

3. In a port light screen, a collar provided 45 with an inturned flange, a gauze-like sheet, a ring on the peripheral portion of said sheet, said ring and sheet being adapted to be seated in the interior of said collar on said flange, and means on said collar adapted 50 to project into the same to retain said sheet seated on said flange.

4. In a port light screen, a collar provided with an inturned flange, a gauze-like sheet, a ring, the latter and said sheet being adapted 55 to be seated on and secured to said flange, and a handle like device for said sheet consisting of a bail and an ear on which the latter is mounted, and means for connecting said ear with said ring.

5. In a port light screen, a collar provided with an inturned flange, a gauze-like sheet, a ring, the latter and said sheet being adapted 60 to be seated on and secured to said flange, and a handle-like device for said sheet consisting of a bail, an ear on which the latter is mounted, and means for connecting said ear with said ring, said means being common fastenings for said ears with said ring and for the latter, and said sheet with said 65 flange.
